COMBINED WINDOW SHADE, CURTAIN, AND DRAPERY SUPPORT

Ernest De Nicolais, New York, N. Y.

Application April 1, 1940, Serial No. 327,149

3 Claims. (Cl. 156—27)

This invention has to do with accessories for windows and comprehends an improved cooperative means for supporting window curtains, draperies and shades.

The invention is directed to an improved supporting means for window shades, curtains and draperies and provides shade brackets and drapery rods which are mounted for vertical sliding movement to permit of the lowering thereof whereby the same may be reached from the floor to facilitate the emplacing of the shades, curtains and draperies thereon and the removal of the same therefrom without the hazard incident to the necessity of having to climb upon ladders, chairs, stools or the like.

The invention further resides in the provision of an improved supporting means of the character set forth and for the purpose specified which is comparatively simple in construction and mode of operation, which may be readily assembled and installed and which means is highly efficient for its intended purpose.

With the above enumerated and other objects in view, the invention is more fully described in the following specification and illustrated in the accompanying drawings in which:

Fig. 1 is a perspective view of the supporting means applied to a window and illustrating in full lines the shade brackets and curtain and drapery rods in their elevated supporting position, the same being shown in dotted lines in the lowered position.

Fig. 2 is an enlarged fragmentary plan view.

Fig. 3 is an enlarged fragmentary sectional view taken approximately on the line 3—3 of Fig. 4.

Fig. 4 is an enlarged fragmentary side view.

Fig. 5 is an enlarged fragmentary front view.

Referring to the drawings by characters of reference, 10 and 11 designate a pair of vertically disposed guide elements which are respectively secured to opposite side stiles A and B of a window frame and which guide elements, as illustrated, are in the form of cross sectionally channel shaped rails each having notched upper and lower ends for receiving a screw 12 or equivalent means for securing the rails respectively to the side stiles of the window frame. The outer edges of the guide elements 10 and 11 are provided with lateral outwardly projecting flanges 13.

A slide member 14 is provided for each rail or guide element 10 and 11 and which slide members are each preferably formed from a length of metal bent upon itself to provide a vertically disposed outer tubular portion 15 and inner

mating terminal portions 16 cooperatively embracing the flanges 13 of the guide elements for vertical guided sliding movement thereon.

Shade bracket elements 17 and 18 are provided which are welded or otherwise secured respectively to the slide members 14 between the tubular portion 15 and the terminal portions 16 thereof and which brackets are provided with depending inwardly offset shade roller engaging terminals 19 and 20.

A curtain rod is provided which consists of an intermediate tubular section 25 and opposite end sections 26 each of which end sections has a terminal 27 telescopically fitted within the intermediate tubular section with the opposite terminal 28 directed rearwardly and formed with a depending extremity 29 fitted within the tubular portion 15. Drapery supporting rods are also provided, each of which is composed of a tubular section 30 which is internally threaded at the opposite ends to receive at one end an ornamental tip 31 having a threaded shank 32. The opposite end of the tubular section receives the threaded terminal 33 of a rod section 34 having a rearwardly directed terminal 35 formed with an eye 36 at the extremity thereof which engages over the depending extremity 29 of the curtain rod section 26 and which rests upon the upper end of the tubular portion 15 of the slide member.

Each slide member is also provided with a depending stem 40 which, as illustrated, is formed as a continuation of the depending extremity 29 and which carries at its lower end a head 41 which is preferably of rectangular form and provided with a set screw 42, said heads being swiveled on the stems 40 between the collars 43 and 44. The stems 40 are also provided with collars 45 upon which the slide members rest and by which they are adjustably supported on the stems.

Substantially U-shaped yokes 48 are carried by the lower ends of the guide elements 10 and 11 and said yokes each includes a pair of forwardly directed parallel arms 49 which are spaced apart a distance to receive the head 41 therebetween.

The arms 49 are respectively provided with notches 50 to receive the shank of the set screw 42 so as to provide detent means at the lower ends of the stems 40 and guide elements for releasably retaining the slide members 14 and the shade brackets and curtain and drapery rods in their uppermost supporting position as illustrated in full lines in Fig. 1. By disengaging the set screws 42 from the notches 50 and turning the heads and rods 40 with the set screws projecting forwardly, the guide elements and rods

and brackets carried thereby may be lowered to the dotted line position illustrated in Fig. 1 whereby they may be readily reached from the floor to facilitate the emplacing of the shades, curtains and draperies thereon and the removal of the same therefrom without the necessity of climbing upon ladders, chairs, stools or the like. After the draperies, curtains and shades have been positioned on the rods and brackets, the stems 40 are employed to raise the guide elements to their uppermost supporting position, the stems 40 and heads 41 being turned so as to engage the set screws 42 in the notches 50, the set screws being then tightened to lock the heads in place. It is, of course, to be understood that the drapery rod sections 30 which are in the form of arms, as illustrated, may be replaced, if desired, by a single tubular section to provide a continuous rod.

What is claimed is:

1. In an assembly for supporting window curtains, a pair of vertically disposed guide elements secured to the opposite side stiles of a window frame, slide members mounted for vertical sliding movement with reference to said guide elements, a curtain rod consisting of an intermediate tubular section and opposite end sections telescopically fitted within the ends of the tubular section and having rearwardly and downwardly extending end portions on which the slide members are mounted respectively at the upper ends of the downwardly extending portions, heads swivelly mounted on the lower ends of said downwardly extending portions, a pair of notched arms carried by each of said guide elements at the lower ends thereof between which pairs of arms the said heads are slideable respectively, and means carried by said heads adapted to engage in the notches of said arms for releasably retaining said curtain rod and slide members in their uppermost position and when released permitting of the lowering of said cur-

tain rod and slide members for facilitating the hanging of curtains on said curtain rod.

2. In an assembly for supporting curtains and draperies, a pair of vertically disposed guide elements secured to the opposite side stiles of a window frame, slide members mounted for vertical sliding movement with reference to said guide elements, a curtain rod consisting of a horizontal forward portion, depending raising and lowering stems on which the slide members are mounted respectively and horizontal rearwardly directed portions intermediate the forward portion and the stems, drapery rods having rearwardly directed terminal eyes swingably engaging the stems and supported upon said slide members respectively, and interengageable means at the lower ends of said stem and guide elements for releasably retaining said slide members in their uppermost supporting position and when released permitting of the lowering of said rods for facilitating the hanging of curtains and draperies thereon.
3. In an assembly for supporting window shades, curtains and draperies, a pair of vertically disposed guide elements secured to the opposite side stiles of a window frame, slide members mounted for vertical sliding movement with reference to said guide elements, a curtain rod connected with said slide members, raising and lowering stems depending from the slide members, detent means swivelly carried by the lower ends of said stems and securing means at the lower ends of said guide elements engageable with the detent means for releasably retaining said slide members in their uppermost supporting position and when released from engagement therewith by swinging of said detent permits of the lowering of said curtain rod and slide members for facilitating the hanging of curtains on said curtain rod.

ERNEST DE NICOLAIS.
